UNITED STATES PATENT OFFICE.

HENRY E. SHAFFER, OF ROCHESTER, NEW YORK.

CHANDELIER.

SPECIFICATION forming part of Letters Patent No. 248,114, dated October 11, 1881.

Application filed January 19, 1881. (No model.)

To all whom it may concern:

Be it known that I, HENRY E. SHAFFER, of Rochester, Monroe county, New York, have invented a certain new and useful Improvement 5 in Chandeliers; and I do hereby declare that the following is a full, clear, and exact description of the same, reference being had to the accompanying drawings, in which—

Figure 1 is an elevation of a chandelier showing my improvement. Fig. 2 is a cross-section of the hanger and a plan of the lamp-fixture. Fig. 3 is an elevation of one of the heads to which the lamps are attached. Fig. 4 is a section showing the end of one of the arms and 15 the lamp-base fitted thereto. Fig. 5 shows one of the lamps removed from place and in position for use as a common stand-lamp.

The object of my invention is to so construct a chandelier that combined stand and bracket 20 lamps, such as are described and shown in Patent No. 227,731, may be attached thereto, thereby forming a complete chandelier, and may be detached therefrom, thereby enabling said lamps to be used as stand or bracket 25 lamps at pleasure.

The chandelier-fixture consists of an ordinary hanger, A, to which at the bottom are attached the arms B B, that support the lamps C C.

30 The fixtures shown in the drawings are trumpet-shaped arms, radiating from a hub placed upon the hanger; but any other desired form may be used adapted to the purpose.

On the outer ends of the arms are disks or 35 heads a a, of a diameter as large as or a little larger than that of the bases of the lamps.

On the faces of the disks, near the top, are screws, studs, or hooks b b, upon which the lamps are hung, and at the bottom are circular flanges or equivalent lugs c c, within which

the bases of the lamps fit to prevent the lamps from tilting or swinging.

The lamps are jointed in the standard, and have locking devices or springs, by which they may be turned into the right-angled position shown in Fig. 1 or into the vertical position shown in Fig. 5. The bases of the lamps also have catches, which hook onto or engage with the screws b b on the fixtures.

By the construction of the chandelier as 50 above described the lamps, when turned into the right-angled position, can be readily attached to the arms, and in this condition an elegant chandelier is produced. Whenever desired the lamps can be detached and used independently, either as bracket or stand lamps. 55

If desired, other forms of bracket-lamps may be used instead of the lamps above described.

Having thus described my invention, what I claim as new, and desire to secure by Letters Patent, is—

1. In a chandelier, the arms or equivalent fixtures B B, having at their outer ends heads or bearings of sufficient size to receive the bases of lamps, said heads having screws, studs, 65 or hooks projecting therefrom for attaching the lamps, as herein shown and described.

2. A chandelier consisting of the hanger A, arms or equivalent fixtures B B, provided with disks or heads a a, and the lamps C C attached 70 to said disks or heads, as herein shown and described.

In witness whereof I have hereunto signed my name in the presence of two subscribing witnesses.

HENRY E. SHAFFER.

Witnesses:

R. F. OSGOOD,
JACOB SPAHN.
